(57) **CLAIM**

The ornamental design for packaging for batteries, as shown and described.

DESCRIPTION

FIG. 1 is a top perspective view of a packaging for batteries showing our new ornamental design;

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

(Continued)

The figures are lined for the colors black and copper, wherein black is represented by a solid fill and copper is represented by cross-hatching.

The broken lines shown represent unclaimed subject matter and form no part of the claimed design.

The claim is shown with a symbolic break in its width. The appearance of any portion of the article between the break lines forms no part of the claimed design.
